UNITED STATES PATENT OFFICE.

TORSTON ALFONSO GYLSDORFF, OF DETROIT, MICHIGAN.

REAMER.

1,334,898.

Specification of Letters Patent. Patented Mar. 23, 1920.

Application filed June 27, 1919. Serial No. 307,051.

To all whom it may concern:

Be it known that I, TORSTON ALFONSO GYLSDORFF, a citizen of the United States, residing at Detroit, in the county of Wayne 5 and State of Michigan, have invented new and useful Improvements in Reamers, of which the following is a specification.

The object of my present invention is the provision of what may be properly denominated a floating reamer; the said floating reamer being materially advantageous in that the reamer is held firm and steady in the holder, and yet is enabled to follow or accommodate itself to the hole that is being reamed.

To the attainment of the foregoing, the invention consists in the novel combinations and adaptation of parts hereinafter described and definitely claimed.

20 In the accompanying drawings, hereby made a part hereof:

Figure 1 is a side elevation of the reamer and complementary holder constituting the best practical embodiment that I have as yet 25 devised.

Fig. 2 is a longitudinal-central section of the same, partly in elevation.

Fig. 3 is a transverse section, taken in the plane indicated by the line 3—3 of Fig. 2. 30 Similar numerals of reference designate corresponding parts in all of the views of the drawings.

The reamer is numbered 1, and its holder 2. In the heel end of the reamer is a socket 3 that describes, by preference, more than half of a hollow sphere, and in said socket is carried and retained an anti-friction ball 4. At intermediate points in its length the reamer 1 is provided with depressions 5; 35 the said depressions being preferably in the same transverse plane, and preferably, though not necessarily, equi-distant, as illustrated.

In the holder 2 is a socket 6 for the reception of the reamer or reamer shank 1, and opposed to the inner end wall 7 of said socket is a steel washer 7^a in which is a depression 8, designed to seat the ball 4. At 45 9 in the forward portion of the holder 2 are four (more or less) radial and threaded bores in which are disposed screw plugs 10, kerfed at their outer ends, as indicated by 50 11, and equipped with inner reduced end portions 12. In the inner smooth portions 55 of the bores 9 are balls 13, designed to coöperate with the depressions 5 of the reamer shank 1, and back of said balls 13 are

springs 14 which surround the reduced end portions 12 and are interposed between the balls 13 and the major portions of the plugs 10, as illustrated. Manifestly the said springs 14 are calculated to yieldingly hold the balls 13 to their work in such manner that under stress the balls are adapted to give readily outward. There is sufficient play between the balls 13 and the plugs 10 to permit the reamer to float in either direction; it being understood here that the springs 14 are of sufficient strength to hold the reamer firm and steady, while permitting the reamer to 65 accommodate itself to or follow the hole that is being reamed.

Manifestly the interposition of the steel-washer 7^a, slightly smaller in diameter than the socket 6, between the ball 4 and the end 75 wall 7 of the socket enables the end of the reamer to float as well as the body thereof.

Having described my invention, what I claim and desire to secure by Letters-Patent is:

1. A reamer having equi-distant depressions in its side in the same transverse plane and also having a socket in the center of its heel end in combination with a holder having a longitudinal socket and also having 85 radial bores reaching outwardly from the socket to the outer side of the holder, the outer portions of said bores being threaded and the inner portions thereof smooth, a washer, of less diameter than the socket, opposed to the end wall of the socket, a ball disposed in the end socket of the reamer and a depression in said washer to enable the heel end of the reamer to float, balls disposed in the radial bores of the holder and 90 coöoperating with the depressions in the side of the reamer, screw plugs arranged in the outer portions of the radial bores and having reduced inner ends, and springs confined in the bores and surrounding said reduced 95 inner ends and interposed between the major portions of the plugs and the balls at the side of the reamer.

2. The combination of a reamer holder, a reamer disposed and movable laterally in 105 the holder, spring-pressed balls coöoperating with the holder and the side of the reamer to enable the latter to float in the reamer, a washer movable edgewise in the holder and between the end of the reamer and the same 110 and a ball between said reamer end and washer.

In testimony whereof I affix my signature
TORSTON ALFONSO GYLSDORFF.
